UNITED STATES PATENT OFFICE.

JOHN S. V. BICKFORD, OF CAMBORNE, ENGLAND.

APPARATUS FOR EFFECTING COMBUSTION OF LIQUID FUEL FOR FURNACES OR THE LIKE.

SPECIFICATION forming part of Letters Patent No. 631,612, dated August 22, 1899.

Application filed May 8, 1899. Serial No. 715,982. (No model.)

To all whom it may concern:

Be it known that I, JOHN SOLOMON VIVIAN BICKFORD, engineer, a citizen of England, residing at Camborne, Cornwall, England, have 5 invented certain new and useful Improvements in Apparatus for Effecting Combustion of Liquid Fuel for Furnaces and the Like, (for which I have applied for a patent in Great Britain, dated October 25, 1898, No. 22,437,) 10 of which the following is a specification.

My invention relates to apparatus for effecting combustion of liquid fuel for heating furnaces, crucibles, retorts, and the like, as I shall describe, referring to the accompanying 15 drawings.

Figure 1 is a longitudinal section of apparatus according to my invention. Fig. 2 is an end view of the air-nozzle and fuel-pipe, and Fig. 3 is a section thereof on the line 3 3 20 of Fig. 1.

a is a chamber having a removable cover b and having in its bottom a bed c of refractory material, such as fire-clay.

d is a pipe projecting into the chamber a. 25 This pipe is constructed at its inner end portion with a central contracted orifice e and a slit f in line with a slit g, extending some distance along the lower side of the pipe d. A pipe h terminates in a downwardly-directed 30 bend, opening over the pipe d a little behind its end. The pipe d is connected to a fan or blower of any known suitable kind, by which a current of air is sent along the pipe and is discharged by the central contracted orifice e 35 and the slits f and g. The pipe h is connected to a reservoir in which oil or other liquid fuel is maintained at a constant level, so that a regulated supply of the liquid flows along the pipe h and is discharged on the upper

side of the pipe d, over which it flows, passing around to the under side, where it is met and atomized by the current of air issuing by the slit g. 40

At first starting the working of the apparatus burning fuel, which may be a wad of asbestos soaked in oil or other combustible liquid, is placed on the bed c under the slit g. This burning fuel ignites the mixture of air and atomized liquid, and the flame receives additional air issuing from the hole e 45 and slit f, a powerfully-heating flame being thus directed through an opening j at the opposite side of the chamber a into a furnace or chamber containing a crucible, retort, or the like. 50

Having thus described the nature of my invention and the best means I know of carrying the same into practical effect, I claim—

An apparatus for the combustion of liquid fuel, consisting of a chamber having a refractory bed and an opening at one side, an air-supply pipe projecting into the chamber at the opposite side and constructed at its inner end portion with a longitudinal slit in its under side, a contracted orifice and a slit leading from said contracted orifice to said longitudinal slit, and a liquid-fuel-supply pipe terminating in a bend which delivers the liquid fuel upon the inner end portion of said air-supply pipe, substantially as described. 60 65 70

In testimony whereof I have hereunto set my hand in presence of two subscribing witnesses.

JOHN S. V. BICKFORD.
